UNITED STATES PATENT OFFICE.

ANTON LANDGREBE, OF NEW YORK, N. Y.

APPARATUS FOR DISPENSING BEVERAGES.

1,137,495.

Specification of Letters Patent. Patented Apr. 27, 1915.

Application filed February 4, 1914. Serial No. 816,486.

To all whom it may concern:

Be it known that I, ANTON LANDGREBE, a citizen of the United States, and a resident of the city of New York, Van Nest, borough 5 of the Bronx, in the county of the Bronx and State of New York, have invented a new and Improved Apparatus for Dispensing Beverages, of which the following is a full, clear, and exact description.

10 This invention relates to beer apparatus and has particular reference to means for cooling and dispensing beverages and especially beer.

15 Among the objects of the invention is to provide connections between a barrel or series of barrels of beer in a cellar and the faucets at the bar on a higher floor, such connections being of a peculiar construction adapting them especially for being readily 20 cleansed and kept in a sanitary condition.

25 A further object of the invention is to provide a peculiar means for cooling the beer as it passes through the aforesaid connections, and though the connections comprise principally straight parallel sections of tubing as distinguished from cumbersome expensive and unsanitary coils, the beer in passing therethrough will be thoroughly cooled.

30 The foregoing and other objects of the invention will hereinafter be more fully described and claimed and illustrated in the drawings forming a part of this specification in which like characters of reference 35 indicate corresponding parts in all the views, and in which—

Figure 1 is a rear elevation of an apparatus made in accordance with this invention, parts being broken away to show the construction; Fig. 2 is a vertical transverse section on the line 2—2 of Fig. 1; Fig. 3 is a transverse horizontal section on the line 3—3 of Fig. 1; Fig. 4 is a fragmentary vertical section of a detail on the line 4—4 of Fig. 3; Fig. 5 is a horizontal section on the line 5—5 of Fig. 4; Fig. 6 is a view of a modification corresponding to Fig. 2; Fig. 7 is a sectional view of a detail of Fig. 6; and Fig. 8 is a detail view of a part of the 50 device shown in Fig. 2 and described below.

The several parts of the device may be made of any suitable materials, and the relative sizes and proportions, as well as the general design of the mechanism, may be varied to a considerable extent without departing from the spirit of the invention

hereinafter more fully described and specifically claimed.

Referring more specifically to the drawings for a description of the mechanism, I 60 provide a bar or counter 10 of any suitable or approved construction at the rear portion of which are arranged any suitable number of faucets 11 for the dispensing of beer or other commodities from barrels or 65 casks 12 in the cellar or basement.

In any usual or approved manner the contents of the barrel are made available by the use of compressed air delivery mechanism (not shown), but including a flexible hose 70 connection 13 extending into the cask or barrel and having its upper end connected to a section of pipe 14 detachably connected by means of a coupling 15 of any suitable nature to a pipe 16 leading upwardly there- 75 from through the floor 17.

Each pipe 16 constitutes one member of a vertical series of parallel pipes 18 shown in Fig. 2 as nine in number. Said pipes 18 are all straight for the purpose of facilitating the cleansing thereof, and each two adjacent pipes are connected by a peculiar form of coupling head 19 shown best in Figs. 4 and 5. Each head comprises two bosses 20 internally threaded and into which 80 the adjacent ends of the two pipes secured thereto are screwed, and the opposite end of the head 19 from the ends of the pipes is closed by a plug 21 removably screw threaded into it. For this purpose the main portion of the head is cylindrical. Upon removing the plugs 21 from the opposite upper and lower ends of the series of pipes, each of said pipes is open for free cleansing. The last pipe 18 of the series is connected at its upper end to a T 22 having a removable plug 21' in alignment with the axis of said pipe and having connected at its lateral end one of said faucets 11, said connection being made by a shouldered 95 coupling 23 whereby the faucet may be readily removed for cleansing or renewal.

The series of pipes 16 and 18 are maintained in substantially the same plane and in stationary position by any suitable means including a bridge or arch 24 coöperating with the upper ends of said pipes and embracing the same. The pipes are supported directly upon the bridge as, for instance, by means of collars 25 extending from the pipes 105 and resting upon the arch. The arch is shown in Fig. 2 as being preferably secured 110

within the structure of the counter 10, this portion of the counter being employed as a cooling tank 26, the walls of which may be made of any suitable material for the purposes of refrigeration and cleanliness. The ice tank 26 may comprise in its construction an inner lining of charcoal, mineral wool, cork or the like, indicated at 27, for the purpose of making a substantially airtight layer 10 of packing.

The pipes above referred to extend directly through the bottom of the ice tank 26 through a stuffing box 28 of any suitable construction, and said pipes continue directly downwardly through another stuffing box 29 at the top or upper end of an auxiliary ice tank 30 below the floor 17 or in the basement of the building. The lower ends of the pipes extend through the bottom of the tank 30 through a stuffing box 31, the bottom of the tank 30 being supported above the basement floor upon a framework 32 of any suitable nature, giving room for the barrels or casks below or adjacent thereto. 20 The removable plugs 21 at the lower ends of the pipes are easily reached by the operator between the casks and the bottom of the tank 30 for the purpose of their removal and replacement. The tank 30 is or may be of substantially the same construction as the tank 26 described above with respect to its cooling and sanitary properties, and is designed to be filled with broken ice or ice and water through a door 33 adjacent its top. The tank 30 is likewise filled with ice or ice and water of any suitable temperature through a removable panel or lid 34 at its top.

At 35 I show any suitable form or construction of drain pipe having communication at several points with the two cooling tanks 26 and 30. For instance, the drain pipe 35 is connected to the upper tank at points 36, 37 and 38, whereby said tank may be drained of the cooling water at different elevations. Likewise connections are made with the tank 30 at points 39, 40 and 41 for similar purposes. The drain pipe is also provided with a plug 42 whereby a hose may be connected to the drain pipe, said hose having its other end connected to any one of the heads 19 for flushing out the cooling pipes 16 and 18, in an easy, rapid and sanitary manner.

Instead of relying upon broken ice or ice water in separate tanks 26 and 30, I may employ a single tank in or through which the pipes may extend continuously, and in any of said tanks I may provide a system

of ammonia pipes for cooling purposes instead of using the ice. In Fig. 6 I show an arrangement whereby a series of pipes 18' are inclosed in the tank 26', the adjacent pipes 18' being connected by means of U-heads 19', the ends of which are connected to the respective pipes by means of shouldered couplings 20'. The uppermost pipe 18' in this system is detachably connected to the faucet 11 by means of a coupling 22' and the lowermost pipe 18' is connected detachably by a vertical coupling 15' to the discharge mechanism for the casks or to another system of pipes 18' in the basement. Upon detachment of the couplings 15' and 22', the entire system of pipes 18' with their U-heads 19' may be lifted bodily 75 out through the top of the tank 26' by lifting away the lids 34'. The several pipes 18' may then be readily detached from the heads by unscrewing the couplings 20', and since these pipes are all straight they are 80 easily swabbed or cleansed and they may be readily assembled again for the purpose of making a new connection. This figure also shows a coil of ammonia pipe 43 of any suitable or well known construction, whereby the air within the tank is cooled to any desired temperature for the purpose of cooling the beer passing through the system of pipes 18'. This tank is maintained practically airtight, and for the purpose of allowing the warm air to pass therefrom preliminary to the act of refrigeration, I may provide a vent pipe 44.

Having thus described my invention, I claim as new and desire to secure by Letters Patent:—

In apparatus of the character set forth, the combination of a plurality of straight parallel pipes having smooth interior surfaces, and means connecting the ends of the pipes each to each so as to provide a continuous circulation and communication throughout all of the pipes, said connecting means including a hollow cylindrical coupling head having a pair of internally threaded bosses receiving the adjacent pipe ends and a flat circular plug removably secured in the end of the head opposite the open ends of the pipes in said bosses.

In testimony whereof I have signed my name to this specification in the presence of two subscribing witnesses.

ANTON LANDGREBE.
